L. M. STEARNS.

LOCKING DEVICE FOR SHELVING.
APPLICATION FILED JUNE 10, 1903.

949,288.

Patented Feb. 15, 1910.

UNITED STATES PATENT OFFICE.

LINCOLN M. STEARNS, OF JAMESTOWN, NEW YORK, ASSIGNEE TO ART METAL CONSTRUCTION COMPANY, OF JAMESTOWN, NEW YORK, A CORPORATION OF NEW YORK

LOCKING DEVICE FOR SHELVING.

949,288.

Specification of Letters Patent. Patented Feb. 15, 1910.

Application filed June 10, 1909. Serial No. 501,265.

To all whom it may concern:

Be it known that I, LINCOLN M. STEARNS, a resident of Jamestown, in the county of Chautauqua and State of New York, have 5 invented a new and useful Improvement in Locking Devices for Shelving; and I do hereby declare the following to be a full, clear, and exact description thereof.

My invention relates to a locking device 10 for shelves and more especially to shelves employed in connection with book-racks where it is desired to adjust the shelves at different heights.

The object of my invention is to provide 15 a locking device for shelves of this character in which the shelves when once adjusted in position are firmly and positively locked so that there is no liability of their being displaced or released by the insertion or 20 withdrawal of the books, or other objects to be supported thereon.

To these ends my invention comprises, generally stated, a suitable frame or casing, a removable shelf supported therein, with 25 means for supporting the shelf at different heights in said casing, and a vertically movable bar having locking devices adapted to engage the shelf and lock it securely in position in one position of said bar and in the 30 opposite position leaving the shelf free to be removed.

Referring to the drawings Figure 1 is a perspective view of a portion of a case with my invention applied thereto; Fig. 2 is 35 a view of the shelf removed; Fig. 3 is an enlarged detail of the locking device when in its locked position; and Fig. 4 is a like view showing it in unlocked position; and Fig. 5 is an enlarged detail in perspective 40 of the locking device.

My invention is applicable to many different forms and styles of cases and shelves, and I do not wish to limit myself in any way to the particular style of case or shelf 45 in connection with which my invention is illustrated, as these may be varied in many different ways according to the circumstances.

The numeral 2 designates a suitable case 50 or rack for containing the books 3 or other article to be stored therein. The case may be made up of metal plates secured together in the form illustrated, or the case may be made up in skeleton form, and while I have

illustrated the case and the different parts 55 as made of metal, wood may be employed if desired for many of the parts. The shelf 4 is what is commonly known as a roller-shelf and may be made up of side bars 8 and front and rear bars 9 and 10, the rollers 60 11 being properly supported therein to relieve the friction in the insertion and withdrawal of the books. The inner ends of the side bars 8 have the projecting portions 12 which are adapted to enter the apertures 65 13 formed in the channels 14 secured to the rear of the casing.

Secured to the casing 2 are the hollow members or channels 15, said channels being provided along their inner flanges with the 70 apertures 16, said apertures being arranged at suitable intervals apart to give the desired adjustment to the shelves. Where a channel is employed the outer flange serves as a striking bar for a door where doors are 75 employed. The shelf 4 is provided with the extensions 17 which are adapted to enter the apertures 16 in the channels 15 and said extensions are provided with the notches 18. These apertures 16 form the supports at 80 different heights to support the shelves. Within the channel 15 is the locking-bar 19 which may be in channel form and said locking-bar is movable vertically within the hollow member or channel 15. This is accomplished by means of the studs 20 on said locking member, said studs having, if desired, the knobs 21. These studs engage the slots 22 in the channel 15. These slots 22 have the recess 23 to hold the locking bar 90 in its released or raised position, as indicated in Fig. 4. The inner flange of the locking-bar is formed with notches 24 which provide the locking tongues or lugs 25 adapted to engage the notches 16 in the extensions 95 17 of the shelves when the locking-bar is lowered, as indicated in Figs. 3 and 5.

When the shelf is in position in the case and locked therein, the locking-bar will be lowered with its locking tongues engaging 100 the notches in the extensions of the shelves, thereby holding the shelf against displacement by the withdrawal of the book. When it is desired to raise or lower the shelf to a different height, the operator by grasping 105 the knobs 23 lifts the locking-bar and by moving the studs 20 into the recess 23 of the slot the locking bar is held supported in

its raised position. By this upward movement of the locking-bar the locking tongues have been lifted out of the notches of the extensions 17 and by moving the shelf inwardly slightly said extensions 17 are withdrawn from the apertures 16 of the hollow bar or channel 15 and the extensions 12 on the inner ends of the shelf are moved farther into the channels 14. The shelf may then be withdrawn from the openings in the channels 14 and raised or lowered the desired extent, when the extensions 12 are inserted in the proper openings in the channels 14 and the front extensions 17 are moved into the proper apertures 16 of the hollow bars 15 whereupon the locking bars are again lowered and the locking tongues thereon engage the notches of the extensions 17 to secure the shelf in position.

The arrangement of the parts and details of construction may be varied without affecting the scope of my invention and I do not wish to limit myself in any way to the details of construction illustrated and described.

What I claim is:

1. The combination of a suitable case, a removable shelf supported therein having one element of a positive interlocking connection, supports at different heights on said case, and a vertically adjustable locking bar having the other element of an interlocking connection engaging the first named element to hold said shelf in locked position.

2. The combination of a suitable case, a removable shelf supported therein having one element of a positive interlocking connection, supports at different heights on said case, and a vertically adjustable locking bar having lugs attached to engage said element of a positive interlocking connection to hold the shelf in locked position.

3. The combination of a suitable case, a hollow support, having seats formed therein, a shelf having a projecting portion adapted to engage said seats, and a locking bar within the hollow shelf support adapted to

engage the projection on said shelf and lock it in position.

4. The combination of a suitable case, a shelf support having seats formed therein, a shelf having a projection adapted to engage said seats, said projection having a notch therein and a locking bar having an overhanging lug adapted to engage said notch.

5. The combination of a suitable case, a channel member secured thereto having seats formed in one of its flanges, a locking bar movable within said channel member, and a shelf having a projection adapted to enter the openings in said flange, said locking bar adapted to engage said projection to lock said shelf.

6. The combination of a suitable case, a channel member supported thereby having seats formed in one of its flanges, a shelf having a projection adapted to engage said seats, and a vertically movable locking bar in said channel member adapted to engage said projection to lock said shelf.

7. The combination of a suitable case, a channel member carried thereby having seats formed in one of its flanges, a shelf having a projection adapted to engage said seats, and a vertically movable locking member within said channel member having engaging lugs to engage said projection on said shelf.

8. The combination of a suitable case, a channel member carried thereby having seats formed in one of its flanges, a shelf having a projection adapted to engage said seats, and a vertically moving channel bar within said channel member, said channel bar having engaging lugs formed on one of its flanges adapted to engage the projection on said shelf.

In testimony whereof, I the said LINCOLN M. STEARNS have hereunto set my hand,
LINCOLN M. STEARNS.

Witnesses:
